DESIGN FOR A CONTAINER

Harold R. Hendy, Los Angeles, Calif.

Application July 24, 1933, Serial No. 48,801

Term of patent 7 years

To all whom it may concern:

Be it known that I, HAROLD R. HENDY, a citizen of the United States, residing in Los Angeles, county of Los Angeles, State of California, have invented a new, original, and ornamental Design for a Container, of which the following is a specification, reference being had to the accompanying drawings forming part thereof.

Fig. 1 is a view in plan showing the container with which my design is concerned.

Fig. 2 is a view in side elevation showing the container with which my design is concerned.

Fig. 3 is a view in central vertical section and elevation showing the container with which my design is concerned.

I claim:

The ornamental design for a container, as shown.

HAROLD R. HENDY,
